UNITED STATES PATENT OFFICE.

FRITZ ALDENDORFF, OF BERLIN-WILMERSDORF, GERMANY, ASSIGNOR OF ONE-FOURTH
TO PAUL KOLISCH, OF NEW YORK, N. Y.; CHARLOTTE ALDENDORFF SOLE HEIR OF
SAID FRITZ ALDENDORFF, DECEASED.

AUTOMATIC TELEPHONE SYSTEM.

Original application filed February 14, 1922, Serial No. 536,504, now Patent No. 1,641,145, dated September 6, 1927, and in Great Britain May 17, 1921. Divided and this application filed April 7, 1926. Serial No. 100,291.

This invention relates in general to telephone systems in which the connections between the subscribers' lines are set up with the aid of electromechanically controlled switching apparatus and is a division of application Serial No. 536,504 (United States Patent #1,641,145). One of the chief objects of the invention is to simplify the mechanical construction of the switching devices. To this end the system is arranged in such a manner that the switches employed for establishing talking connections are uni-motional that is each has wipers that only execute simple rotary motions or, if preferred, straight line motions. In accordance with this invention bi-motional switches may be entirely dispensed with, without perceptibly slowing down the speed with which the connections are obtained. Another feature of the invention is that a calling party selects the desired number, but not actually the desired line, by means of devices which revert to common use as soon as a talking connection is set up between the line of the calling party and the desired line by talking connection switches. The selecting impulses for selecting a desired number are partly sent into a device permanently associated with a talking connection switch, and partly into a wanted line designating device which may be common to a number of talking connection switches.

Another feature of the invention is the use of a switch or switches with a single wiper-driving means, a primary numerical device for selecting any desired group of bank contacts in the switch, and a secondary numerical device for controlling the driving mechanism whilst the wipers are being set onto a certain contact (or set of contacts) in the selected group of bank contacts. Circuit arrangements are provided for enabling one or more secondary devices to be used for controlling the driving mechanism of any one of a number of talking connection switches. A connecting device is provided for connecting a secondary controlling device to any talking connection switch. A connecting device which is arranged to connect an associated switch controlling device to another talking connection trunk as soon as the previous

trunk is connected to a wanted line, is arranged to perform its function of connecting the switch controlling device to another trunk as soon as the associated controlling switch 55 has guided a talking connection switch associated with the trunk onto a line corresponding to the particular number selected by a calling subscriber. The controlling device has a number of contact points which is equal 60 to the number of contact points in one group of bank contacts of the talking connection switch.

The connecting devices or trunk finders are so arranged that the release from a trunk 65 depends firstly on the calling subscriber being connected to said talking trunk and secondly on this trunk being connected to another trunk or to a line leading to a desired subscriber. The release of the trunk finder 70 is effected by a circuit controlled by the release relay of the transitorily engaged finder and by a relay associated with the trunk finder that is de-energized at the moment when a talking connection is extended 75 through the talking connection calling line finder to the wipers of the switch associated with this latter finder. The connection of the calling subscriber is transferred from a transitorily used trunk to the talking trunk 80 at a certain moment. Up to the moment when the connection of the calling subscriber is transferred from the transitorily used trunk to the talking trunk, the release of the line selecting or designating switch is under the control of the release relay associated with the transitorily used trunk. At the moment when the connection of the calling subscriber is transferred from the transitorily used trunk to the talking trunk, the release of the line 85 selecting switch is made dependent on a device associated with the talking connection calling line finder. At the moment when the connection of the calling subscriber is extended through a talking connection calling line finder and its associated trunk to another trunk (or line) the line selecting switch is released. The line selecting or designating switch is released at any moment during the progress of the connection through the transitorily engaged switches by the de-energization 90 of their associated release relay, 95

or, during the progress of the talking connection through the talking connection calling line finder, by the deenergization of a relay associated with this finder. Means are thus provided for properly releasing, at any moment in which the call may be abandoned, all the devices affected in making a call in a system using by-paths for selecting purposes. Further features of the invention will appear 10 hereinafter and in the claims and drawing in which latter Figs. 1 and 2 show the circuits and switches of a complete system employing transistorily engaged marking switches for designating the group and terminal locations of wanted lines in a main line switch. These figures also show a transistorily engaged line finder and a preselecting trunk finder switch and Fig. 3 shows a modification of the auxiliary arrangements for setting a talking connection switch or main switch onto a wanted line or trunk.

Referring to the drawings S represents a calling subscriber, CS is a talking connection calling line finder, WS is a talking connection wanted line finder, T is a talking connection trunk forming a link between the finder CS and the numerical switch WS, TF is a trunk finder, F is a transistorily engaged finder, S' is a units selector or wanted line designating switch. When a subscriber S makes a call his line is first connected by a finder F to a switch S' and his selecting impulses pass through the finder F partly through the associated trunk finder TF into a group selecting device Sg and partly into the units or line selecting device S'. The impulses sent into the group selecting device Sg immediately cause the wipers of the finder WS to start travelling towards the selected 25 group of bank contacts and when they have reached this group they continue travelling until they reach a contact designated by the units selector S'. When they have reached this contact the selected line is tested by a 30 test relay tr associated with the finder WS. If the tested line is free the test relay energizes. Meanwhile the calling line finder CS will have moved its wipers onto the bank contacts corresponding to the line of the calling 35 subscriber S. When the line finder CS has set its wipers onto the calling line and, in addition to this, the test relay tr responds, the line of the calling subscriber S is switched through to the wanted line and the trunk 40 finder TF is caused to set its brushes onto another trunk T which is neither engaged by a conversation nor seized by another trunk finder. The by-path consisting of F, TF and S' may then be used for another connection.

An identifying switch DS is provided for a group of finders F. This identifying switch DS identifies calling lines in the banks of the switches CS and F in such a way that 45 a calling line finder CS will never connect

to any calling line except the one by whose call it is affected.

Another identifying switch DS' is provided for a group of units selectors S'. The identifying switch DS' prevents a called line 70 finder WS from stopping on any wanted line excepting the line selected by the calling subscriber and connected to the finder WS.

The release of the units selector S' depends on the release relay r up to the moment 75 when the calling subscriber's line is found by the line finder CS. At that moment the release of the switch S' is made to depend on a relay 3 associated with the finder CS or on the test relay tr.

The operations involved in establishing a talking connection will now be more fully described. When the calling subscriber S raises his receiver the line relay 4 associated with his line is energized by a current which flows from the positive pole through 4, contact 5 of cut-off relay 6, limb b of calling line, instrument S, limb a of a calling line, contact 7 of cut-off relay, other winding of line relay 4 to the negative pole. The line relay 4 on energizing prepares a stopping circuit by means of its contact 9, closes an operating circuit of a transistorily used finder F at its contact 11, and renders the calling line busy by opening its contact 10. The said operating circuit closed at 11 extends from the positive pole through the interrupter i through 11, starting wire 23, contact 13 of the stopping relay 24, operating magnet 25 of the transistorily used finder F to the negative pole. The operating magnet 25 drives the wipers 26, 27, 28, 29 of the transistorily used finder F forward until they reach the set of bank contacts belonging to the calling line when the current will flow from the negative 100 pole through contact 19 of the relay 30, stopping relay 24, brush 28, stopping wire 31, contact 9, cut-off relay 6 to the positive pole. The relays 6 and 24 are thus energized, the latter relay opening the circuit of the operating magnet 25 at 13, preparing an identifying circuit at its contact 14, preparing a circuit at 15 which extends through the relay 33 and the contact 32 when the relay r is energized, reducing the potential on the stopping wire 31 by closing its contact 16 and extending the subscriber's line a, b to the impulse relay 35 through its contacts 17 and 18. The cut-off relay 6 disconnects the line relay from the subscriber's line at its contacts 5 and 7 and connects itself to the stopping wire through its contact 8 thus making its circuit independent of the contact 9 of the line relay which is opened as soon as this relay is cut off from the calling line as described.

The calling subscriber, over whose line current now flows through the windings of the impulse relay 35 which in turn has energized the release relay r by a circuit extending from 120

the positive pole through 21, *r*, 36, to the negative pole, now commences sending his dialling impulses. The contacts 32, 38, 39, 40, 42 of the release relay *r* are closed and the contacts 34 and 41 of this relay are now open. At the contact 40 a circuit is closed which extends from the negative pole through 40, relay 43, wiper 45 of trunk finder TF, corresponding bank contact, wire 50, relay 51, contact 52 to the positive pole. This circuit helps to control the release of the secondary or units designating switch S' and of the primary or tens designating switch Sg as will herein-after more fully appear.

15 When the calling subscriber sends in his dialling impulses intermittent closures of the contact 22 will take place due to the deenergization of the impulse relay 35 and tens impulses will flow from the positive pole through 22, contact 39, wire 53, off-normal contact 54, slow-acting relay 55, wire 56, wiper 46, corresponding bank contact of trunk finder TF, wire 57, wire 58, operating magnet Sg of the tens designating switch 25 which has a switch arm 59 and an arcuate member 60 adapted for connecting the negative pole to any number of contacts 61, 62, 63 at one and the same time. According to the number of tens impulses sent through the operating magnet Sg fewer or more contacts 61, 62, 63 will be connected to the negative pole by the member 60. If only one tens impulse is sent through the magnet Sg the member 60 will be stepped onto the contact 64 so 35 that the negative pole will not be connected to any of the group designating contacts 65, 66, 67 of the main switch WS by which the connection is established with the wanted line. It will be assumed that the calling subscriber 40 has sent in three tens dialling impulses and that the member 60 has therefore applied the negative pole to the contacts 61, 62 and hence to the contacts 65, 66. As soon as the negative pole is applied to the contact 61 an energizing 45 circuit for the operating magnet 68 of the main switch WS is closed which extends from the negative pole through 61, 65, wiper 69 of the talking connection switch WS, operating magnet 68, interrupter *i* to the positive pole. 50 The wipers will now be driven forward by the magnet 68 until the wiper 69 is driven off the live group designating contacts 65, 66, i. e. until they reach the group of bank contacts in which the particular set of bank contacts is 55 located to which the wanted line is connected.

When the release relay *r* closes its contacts 38 it thereby establishes an energizing circuit for the operating magnet 74 of the calling line identifier DS. This circuit extends from the negative pole through 38, 75, operating magnet 74 to the positive pole. The magnet 74 drives the wipers 76, 77, 78 of the identifier DS forward until the wiper 77 reaches the contact 80 to which the negative pole has been applied by the contact 42 of the

release relay *r* used for the particular connection. A current then flows from the positive pole through the relay 79, wiper 77, bank contact 80, contact 81 of relay 82, contact 42 to the negative pole. The relay 79 opens the operating circuit at contact 82' so that the wipers 76, 77, 78 stop on the bank contacts 83, 80, 84 leading to the particular finder F and trunk finder TF appropriated for the call in question.

When the relay *r* was energized and thus caused the energization of the relay 51 as previously described, it also started the operation of the voice current calling line finder CS by means of a circuit that extends from the negative pole through contact 86, wire 87, bank contact 88, wiper 89 wire 90, contact 91 of the identifying relay 92' operating magnet 93 of the voice current finder CS, interrupter *r* to the positive pole. When the wiper 89 is driven off the bank contact 88 onto the contact strip 94', the circuit of the operating magnet 93 extends from the negative pole through 94', 89, 90, 91, 93, *i* to the positive pole and this circuit remains closed until the identifying relay 92' opens its contact 91 which it will do when the wipers 92, 93, 94 and 95 reach the set of bank contacts that belong to the calling subscriber who has appropriated the switch CS for his call. When this set of bank contacts is reached an identifying circuit is closed which extends from the negative pole through 78 of the identifier DS, 81, relay 82, wiper 44, wire 96, wire 97, contact 98, identifying winding 99, identifying wiper 95, identifying wire 100, wiper 29, contact 14, bank contact 83, wiper 76 of the identifier to the positive pole. The identifying relay 92' is thus energized and opens the circuit of the operating magnet 93 at the contact 91. The identifying relay also closes its contacts 101, 102 whereupon a current flows through the relay 3 in a circuit which extends from the negative pole through the left winding of 3, wire 1, 101, 92, *b*, S, *a*, 93, 102 right winding of 3 to the positive pole. When the relay 3 energizes it opens the contact 98 and closes at its contact 103 a new energizing circuit for the relay 92' which extends from the negative pole through 103 upper winding of identifying relay 92', wire 104, wiper 94, wire 31, contact 9, cut-off relay 6 to the positive pole. Thus, the energization of the relay 92' is now made to depend on the relay 3. Before the contact 98 is opened a new circuit is established for the relay 82 through the contact 108 this circuit extending from the positive pole through 108, 97, 96, 44, 82, 84, 78 to the negative pole. When the relay 3 opens the contact 52 it establishes a new circuit for the relays 43 and 51 which extends through the contact 109 and contact 110 to the positive pole. The circuit of the relays 51 and 43 is thus now made to depend on the test relay *tr*.

It was shown in the foregoing description that the tens dialling impulses go through the slow acting relay 55. The impulses keep the relay 55 energized. When it is first energized it closes its contact 120 to send an impulse through the operating magnet 121 of the units designating switch S'. This impulse serves to move the switch S' out of its normal position so as to open the off-normal contact 54 and to close the off-normal contact 122. When the contact 54 is opened the remaining tens dialling impulses flow through the contact 123 of the relay 55. When all the tens dialling impulses have been sent in, a short pause ensues during which the relay 55 allows its armatures to drop back. When the calling subscriber thereafter sends in the next series of dialling impulses this next series flow from the positive pole through 22, 39, 53, 122, slow-acting relay 123', contact 124, operating magnet 121 to the negative pole. By this means the wiper 125 is set on to the proper units designating contact, say 126 for designating the particular set of bank contacts wanted in the group of bank contacts that has already been designated in the switch WS. When the units dialling impulses commence flowing through the relay 123' this relay energizes and closes an energizing circuit for the relay 128 which extends from the negative pole through 127, 128 to the positive pole. The relay 128 closes its contacts 129, 130, 131, 132. By its contact 129 the relay 128 prepares an operating circuit for the driving magnet 68 of the switch WS. This circuit is closed when the units dialling impulses cease and the relay 123' is deenergized. This circuit extends from the negative pole through the wiper 131' of the wanted line identifier DS' which is operated as will be described presently, bank contact 132', contact 130' of the relay 123', contact 129 of relay 128 (which will have closed a locking circuit for itself extending from the positive pole through 130, 136, 137, 40 to the negative pole), 140, wiper 48, corresponding bank contact of the trunk finder TF, wire 141, contact 142 of the identifying relay 143, driving magnet 68, interrupter *i* to the positive pole of the battery. The driving magnet 68 now drives the wipers 69, 70, 71, 72, 73 forward until the wiper 70 reaches the bank contact 145 designated by the wiper 125 having been set onto the bank contact 126 of the units designating switch S'. An identifying current will then flow from the negative pole through 131' 132', relay 146, wiper 125, contact 126, bank contact 145, wiper 70, right winding of identifying relay 143, wire 148, corresponding bank contact of trunk finder TF, wiper 47, wire 149, bank contact 150, wiper 151 of the wanted line identifier DS' to the positive pole. The identifying relay 143 and the relay 146 are thus energized, the

former relay opening the circuit of the driving magnet 68 at its contact 142, closing a locking circuit for itself which first extends through the contacts 152 and 155 and then through a path leading through the contacts 153, 299 and 103. By means of contact 155 the identifying relay 143 applies the negative pole through 153, 155 to the test relay *tr* and, if the wanted subscriber is free, the test relay *tr* will now be energized by a current flowing from the negative pole through 153, 155, *tr*, 160, wiper 71, test wire of wanted line corresponding to 161, a contact corresponding to 10, associated with the wanted line, cut-off relay associated with the wanted line and corresponding to 6 to the positive pole of the battery. The test relay *tr* on energizing opens at its contact 110 the circuit of the relays 51 and 43 which will have extended at this time from the positive pole through 110, 109, 51, 50, 45, 43, 201, 199 to the negative pole, and upon the armature of the relay 43 dropping back impulses will flow from the positive pole through the interrupter *i*, contact 41, 200, off-normal contact 191, driving magnet 121 to the negative pole. The driving magnet 121 will now continue receiving impulses until it has driven its wiper 125 into the normal position when the off-normal contact 191 will be opened to stop the operation of the magnet 121. When the relay 43 is deenergized as described a current impulse also flows from the positive pole to the interrupter *i*, contact 41, 200, 198, relay 197, to the negative pole. The relay 197 is thus energized to close the circuit of the operating magnet 194 of the trunk finder TF, this circuit extending from the positive pole through *i*, 193, 194 to the negative pole. Whenever an impulse flows through the magnet 194 an impulse will also flow through *i*, contacts 195, 196, upper winding of relay 197 to the negative pole, so that during the transition or stepping of the wipers of the trunk finder TF from one set of bank contacts to the next the relay 197 will be kept energized by an impulse through *i*. When this impulse through *i* ceases the upper winding of the relay 197 will, whenever the wipers strike a set of bank contacts belonging to an engaged or seized trunk, receive current through a contact 250 or 185, wire 251, wiper 49, contact 196 or through a contact corresponding to 192 in another trunk finder and through the relay 197. When the wipers of the trunk finder TF strike a set of contacts that correspond to a free trunk that has not been seized by another trunk finder similar to TF the relay 197 will be deenergized to open the circuit of the driving magnet 194. The moment the wipers of the trunk finder TF are moved away from the set of bank contacts leading to the trunk that was appropriated for the particular call in question the locking circuit of the relay 82 which ex-

tended from the negative pole through 37, 82, 44, 96, 97, 108, to the positive pole was opened. When the relay 82 was energized in the manner hereinbefore described and opened its contact 81 it caused the deenergization of the relay 79 and thus made the calling line identifier DS available for the other calls.

The wanted line identifier DS' had its wipers 151, 270, 131' set onto the bank contacts corresponding to the units designating switch S' in the following manner:—When the relay 128 was energized it closed at its contact 131 an operating circuit extending from the positive pole through i , 131, 281, 282, 280, to the negative pole. At the same time the relay 128 applied the positive pole to the bank contact 283 so that when the driving magnet 280 had driven the wipers 151, 270, 131' onto the set of bank contacts corresponding to S' a stopping circuit was closed which extended from the negative pole through the relay 285, wiper 270, contact 283, contact 132 to the positive pole. The circuit through the relay 285 is opened and the wanted line identifier DS' is made available for other calls at the moment when the identifying circuit through the relay 146 is closed to open at contact 136 the locking circuit of the relay 128 which extends from the positive pole through the lower winding of 128, contact 130, contact 136, wire 137 and through the contact 40 or through the contact 201, 199 to the negative pole. It is thus seen that the wanted line identifier DS' is made available for another call as soon as the talking connection switch WS with which it was coupled through TF has been set onto the bank contacts leading to the line of the wanted subscriber.

The transistorily used finder F is made available for a new call at the moment when the relay 197 is energized in the manner described above, when the contact 36 of the relay 197 is opened and the circuit from the positive pole of the battery through 21, r , 36 to the negative pole is interrupted. The relay r is then deenergized and closes at its contact 34 the circuit leading through the contact 20 of the slow acting relay 33, winding 50 of the relay 30 to the negative pole. The relay 30 is then energized and opens the contact 19 to interrupt the circuit of the relay 24. When the relay 24 is deenergized the impulse relay 35 is disconnected from the calling line at the contacts 17 and 18. The driving magnet 25 will now be reconnected through 13 to the wire 23 which leads to the contacts corresponding to 11 of all the line relays of this particular group of subscribers.

The events involved in establishing a connection through the switch CS, the trunk T and the wanted line selector WS were explained above up to the point where the test relay tr had attracted its armature and opened

the circuit of the relays 51 and 43 at its contact 110. At its contact 164 the relay tr closes the circuit of the ringing relay 171 which extends from the negative pole through 280, 164, ringing relay 171, interrupter i to the positive pole. Ringing current is now intermittently sent from a ringing generator 291 through 174, 180, 73 to the called subscriber's station and back through the wiper 72, contact 178, contact 175 back to the generator 291. When the wanted subscriber responds the relay 170 is energized and at its contact 290 it opens the circuit of the ringing relay 171. The calling subscriber S is now connected through the wipers 92, 93, contacts 101, 102, condensers, contacts 172, 173, contacts 180, 178, wipers 72, 73 to the line of the wanted subscriber and the conversation can proceed.

If the wanted subscriber should be engaged when the wipers of the switch WS are set onto the wanted line the test relay tr will not be energized as was previously described and the busy tone produced by the busy tone apparatus 182, 183 will be sent through the contacts 181, 177, contact 172, 173, contacts 101, 102 to the calling subscriber and this subscriber will then replace his receiver and thus cause the relay 3 to be deenergized. When the relay 3 is deenergized it opens at its contact 103 the circuit of the relay 92' and the cut-off relay 6 and also the locking circuit of the relay 143. If the relay 82 should not have been deenergized by the displacement of the wipers of the trunk finder TF as previously explained its circuit also will be opened at the contact 108 when the relay 3 is deenergized. The holding circuit of the test relay tr which extends through 103 and the contact 299 is also opened at 103.

Should the calling subscriber abandon a call while wipers of the transistorily used switch F are still set on his line the impulse relay 35 will be deenergized to open the circuit of the relay r . The contact 34 which is then closed closes the circuit of the relay 30 to open the contact 19 and deenergize the relay 24 and, if the units designating switch S' should have been displaced by numerical impulses this switch S' will also be restored to normal by impulses that flow from the positive pole through i , 41, 200, 191, driving magnet 121 to the negative pole. When the relay 51 is deenergized on the energization of the test relay tr the auxiliary switch Sg of the main switch WS is immediately restored by impulses that flow from the negative pole through the magnet of Sg , wiper 59, contact strip 300', contact 190, interrupter i to the positive pole. While the auxiliary switch Sg is being restored the circuit of the driving magnet 68 is kept open at the point 299' by a contact controlled by the test relay tr .

It will be obvious that instead of providing a small number of secondary designating switches or units designating switches S' 130

which are common to a group of main switches WS a secondary designating switch S' may be provided for each main switch. The number of secondary designating switches S' will then be greater but the circuit arrangement will then be simpler.

It may also be mentioned that the release of the main switch WS which, as shown in Fig. 1, depends on the deenergization of the release relay *tr*, which in turn is effected by the deenergization of the relay 3, may be made to depend on the replacement of the called subscriber's receiver by means of an auxiliary release relay (not shown) that is operated when the relay 170 is energized and that then prepares a release circuit for WS which takes effect on the subsequent deenergization of 170 caused by the wanted party hanging up.

A modified means for setting the main switch onto the wanted line is illustrated in Fig. 3. In this figure the devices used for setting the main switch only are shown, the circuits and contacts through which the voice current are conducted being omitted. In this figure WS' corresponds to WS in Fig. 1, TF' corresponds to TF in Fig. 1 and a wanted line selector consisting of 4 ten-point switches and comprising the stepping magnets 317, 322 and 333, 334 are associated with the trunk finder TF'. 330 is the impulse relay that receives the dialling impulses from the calling line. When a calling line has been connected through to the wanted line selector and sends in the tens dialling impulses these impulses flow from the minus pole through the contact of the release relay 328, contact 332, 323, stepping magnet 322 (which steps the brushes 319, 326 onto a certain contact, say the third contact 342), to the positive pole. The relay 381 closes the contact 308 and the wanted line connector WS' is then started by a current impulse from the minus pole through 313, operating magnets 312, 308, 310 to the positive pole. The connector WS' now shifts its wipers 310, 311 causing the wiper 310 to contact with the contact strip 65'. When the wiper 310 leaves the initial contact the relay 381 is deenergized, but impulses continue flowing through 313, 312, 307, 65', 310 to the positive pole. The wipers 310, 311 are thus kept moving and whenever the wiper 310 encounters a new strip 65', 66', 67' an impulse is sent from the positive pole through 310, 305, 300 (operating magnet 317) to the negative pole. The magnet 317 moves the wiper 318 until it reaches the contact 342 corresponding to the contact 342 onto which the wiper 319 has been set by the tens impulses. The relay 304 is then energized by a current from the positive pole through 310, 304, 316, 301, 318, 341, 342, 319, minus pole. The magnet 317 then has its circuit opened at 305 and at the same time the positive pole

is connected through 310, 306, to the wiper 311. Each time the wiper 311 encounters a new units contact an impulse is sent through 310, 306, 311, 314, 302, 337, 333 to the minus pole. In the meantime the units connecting impulses will have come in and caused the operating magnet 334 to step the wiper 336 onto a certain contact, say 340. When the wiper 335 reaches the contact 339 corresponding to 340 an impulse will flow through 310, 306, 381, 303, 338, 339, 340, 336 to the negative pole and the relay 381 will then open the circuit of 312 and stop the wipers WS' on the particular line that has been marked by means of the wipers 336 and 319.

I claim:

1. In a telephone system; lines; impulse transmitters associated with said lines; a conversational switch with fixed contacts connected to said lines, movable contacts, and operating means for operating said movable contacts; an impulse receiving designating switch adapted to be set by a said impulse transmitter; starting means for starting said operating means immediately impulses commence being sent into the impulse receiving switch from a said impulse transmitter; and means for controlling the operation of said movable contacts in accordance with the setting of the impulse receiving designating switch.

2. In a telephone system; lines; impulse transmitters associated with said lines; a conversational switch with fixed contacts connected to said lines, other fixed designating contacts, movable contacts cooperating with said designating contacts, and operating means for operating said movable contacts; an impulse receiving designating switch with contacts connected to said designating contacts and adapted to be set by a said impulse transmitter; starting means for starting said operating means immediately impulses commence being sent into the impulse receiving switch from a said impulse transmitter; and means for controlling the operation of said movable contacts in accordance with the setting of the impulse receiving designating switch.

3. In a telephone system; lines; impulse transmitters associated with said lines; a conversational switch with groups of sets of fixed contacts connected to said lines, a fixed designating contact allotted to each said group, a movable contact adapted to cooperate with the designating contacts, and operating means for operating said movable contact; an impulse receiving designating switch with contacts connected to said designating contacts and adapted to be set by a said impulse transmitter; starting means for starting said operating means immediately impulses commence being sent into the impulse receiving switch from a said impulse transmitter; and

means for controlling the operation of said movable contact in accordance with the setting of the designating switch.

4. In a telephone system; lines; impulse transmitters associated with said lines; a conversational switch with groups of sets of fixed contacts connected to said lines, a fixed group designating contact allotted to each said group, a movable contact adapted to cooperate with the group designating contacts and moving means for moving the movable contact over the group designating contacts, an impulse receiving designating switch with bank contacts connected to said designating contacts, a movable contact adapted to cooperate with the bank contacts, and means for setting the movable contact on a desired bank contact in response to impulses from an impulse transmitter; starting means for starting the operation of said moving means immediately impulses from a said impulse transmitter commence affecting the designating switch; and means for controlling the operation of the movable contact of the conversational switch in accordance with the setting of the movable contact that cooperates with said bank contacts. 70
5. In a telephone system; lines; impulse transmitters associated with said lines; a rotary step-by-step conversational switch provided with groups of sets of fixed contacts connected to said lines, a fixed group designating contact allotted to each said group, a rotatable contact adapted to cooperate with the group designating contacts and a stepping magnet for rotating the rotatable contact; a rotary impulse receiving designating switch with bank contacts connected to said designating contacts, a rotatable brush adapted to cooperate with the bank contacts and a brush-moving magnet for setting the brush in response to impulses from an impulse transmitter; starting means for starting the operation of said stepping magnet as soon as impulses from a said impulse transmitter commence affecting the designating switch; and means for controlling the operation of the rotatable contact of the conversational switch in accordance with the setting of said rotatable brush. 75
6. In a telephone system; lines; impulse transmitters associated with said lines; a rotary step-by-step conversational switch provided with groups of sets of fixed contacts connected to said lines, a fixed group designating contact allotted to each said group, a contact-set designating contact for each contact set, a rotatable contact adapted to cooperate with the group designating contacts, a second rotatable contact adapted to cooperate with the contact-set designating contacts, and a driving magnet for driving the rotatable contacts; a primary impulse receiving group-designating switch provided with bank contacts connected to said contact-set designating contacts, a wiper adapted to cooperate with said individual bank contacts, and a wiper-moving magnet for setting the wiper; and means for controlling the operation of said second rotatable contact in accordance with the setting of said wiper. 80
7. In a telephone system; lines; impulse transmitters associated with said lines; a rotary step-by-step conversational switch provided with groups of sets of fixed contacts connected to said lines, a fixed group designating contact allotted to each said group, a contact-set designating contact for each contact set, a rotatable contact adapted to cooperate with the group designating contacts, a second rotatable contact adapted to cooperate with the contact-set designating contacts, and a driving magnet for driving the rotatable contacts; a primary impulse receiving group-designating switch provided with bank contacts connected to said contact-set designating contacts, a wiper adapted to cooperate with said individual bank contacts, and a wiper-moving magnet for setting the wiper; and means for controlling the operation of said second rotatable contact in accordance with the setting of said wiper. 85
8. In a telephone system; lines; impulse transmitters associated with said lines, a conversational switch comprising fixed contacts connected to said lines and divided into groups and members for selecting contact groups; an impulse receiving-group designating device for controlling the selecting operation of said members in accordance with the impulses received; and means for starting the operation of said members as soon as impulses commence being sent from a said transmitter. 90
9. In a telephone system; lines; impulse transmitters associated with said lines; a primary impulse receiving group-designating switch provided with bank contacts connected to

- conversational switch comprising fixed contact sets connected to said lines and divided into groups, and members for selecting a group of contact sets and any individual set in a group; a primary impulse-receiving group designating device for controlling the selecting operation of a said member to select a said group in accordance with impulses received; a secondary impulse-receiving-contact-set designating device for controlling the selecting operation of a said member to select an individual contact-set in accordance with impulses received; and means for starting the operation of the conversational switch as soon as impulses for controlling it commence being received.
10. In a telephone system; lines; impulse transmitters associated with said lines; conversational switches each comprising fixed contact sets connected to said lines and divided into groups, and members for selecting a group of contact sets and any individual set in a group; a primary impulse-receiving group designating device allotted to each conversational switch for controlling the selecting operation of a said member to select a said group in accordance with impulses received; secondary impulse-receiving contact-set designating devices common to a group of conversational switches for controlling the selecting operation of a said member to select an individual contact-set in accordance with impulses received; and means for starting the operation of the conversational switch as soon as impulses for controlling it commence being received.
11. In a telephone system; lines; impulse transmitters associated with said lines; conversational switches each comprising fixed contact sets connected to said lines and divided into groups, and members for selecting a group of contact sets and any individual set in a group; a primary impulse-receiving group designating device allotted to each conversational switch for controlling the selecting operation of a said member to select a said group in accordance with impulses received; secondary impulse-receiving contact-set designating device common to a group of conversational switches for controlling the selecting operation of a said member to select an individual contact-set in accordance with impulses received; and means for temporarily associating any secondary designating device with any conversational switch.
12. In a telephone system; lines; impulse transmitters associated with said lines; conversational switches; group designating means associated with each switch for controlling it to select a group of lines in accordance with impulses sent from a said transmit-

ter; and a device common to a plurality of conversational switches for controlling any switch to select any individual line in a group in accordance with impulses sent from a transmitter and means for starting the operation of a conversational switch immediately upon the receipt of numerical impulses by a group designating means.

13. In a telephone system; lines; impulse transmitters associated with said lines; conversational switches; group designating means associated with each switch for controlling it to select a group of lines in accordance with impulses sent from a said transmitter; and means for starting the operation of a conversational switch as soon as impulses for controlling it commence being received by a group designating means.

14. In a telephone system; lines; impulse transmitters associated with said lines; conversational switches; group designating means for controlling a conversational switch to select a group of lines in accordance with impulses sent from a transmitter; and means for starting the operation of a conversational switch as soon as impulses for controlling it commence being received by a group designating means.

15. In a telephone system; lines; impulse transmitters associated with said lines; conversational switches for selecting groups of said lines and provided with a selecting member that is moved to select a said group only when the second or a higher group of lines is to be selected; and impulse-receiving group designating means for controlling the conversational switches to select a group of lines in accordance with impulses received; and a starting means for starting the operation of a conversational switch as soon as a group designating means commences receiving impulses from a said impulse transmitter.

16. In a telephone system a calling line, called lines, register mechanism comprising a step-by-step switch for registering the numerical designation of a called line, a connector switch having contacts in which the called line terminates, said contacts being arranged in groups with a group designating contact for each group, means responsive to the setting of said register for electrically marking the group designating contact of the called line and for also electrically marking the particular called line individually in the group, and means for causing the brushes of said connector to first hunt for the marked group contact and then for the marked line contact.

In testimony whereof I have affixed my signature.

FRITZ ALDENDORFF.
